ATTORNEY

UNITED STATES PATENT OFFICE

HANS BURMEISTER, OF BERLIN, GERMANY, ASSIGNOR TO PYRENE-MINIMAX CORPORATION, A CORPORATION OF DELAWARE

APPARATUS FOR PRODUCING FOAM

Application filed November 12, 1927, Serial No. 232,786, and in Germany March 31, 1927.

The present invention relates to apparatus for producing foam for fire extinguishing purposes and has for an object to provide improved means for combining powder and water to form foam.

The nature and objects of the invention will be better understood from a description of a particular embodiment of the invention, for the purpose of which description reference should be had to the accompanying drawing forming a part hereof and in which—

The figure is a central sectional view of an illustrative apparatus embodying the principles of the invention.

The apparatus shown comprises a hopper 5 for foam forming powder, which hopper terminates at its bottom in a plurality of restricted outlets 6. Opposite each restricted outlet is a nozzle 7 positioned to cooperate with the outlet to form an ejector. In order to feed the foam forming powder to the ejectors, a suitable spray arrangement 8 is provided above the ejectors so arranged as to wash the desired quantity of powder into the ejectors. As shown, the spray device is formed with a slot 10 extending, preferably, entirely around the same to project a sheet of water outwardly and downwardly, as indicated by the arrows. The nozzles of the spray device are conveniently formed as one integral structure and preferably are supplied by one water inlet, in order that the pressure and, therefore, the quantity of water discharged from both may be maintained in desired ratio. By this arrangement as the water pressure increases, thus increasing the quantity of water fed to each outlet by its corresponding nozzle, the quantity of water discharged by the spray increases simultaneously, thereby to feed a larger quantity of powder.

In the arrangement shown, the nozzle member 11 is formed as a continuous part of the water inlet conduit 12, and may have, for example, four nozzles 7. In the upper end of the nozzle member, a spider 18 is secured to provide suitable support for the bolt 14 adjustably carrying the cone 15, which constitutes the upper member of the spray noz-

zle above described. A lock nut 16 holds the bolt 14 in adjusted position.

Each outlet 6 is preferably tapered and so shaped as to form with the corresponding nozzle 7 an effective ejector.

The foregoing description of a particular embodiment of the invention is illustrative merely and is not intended as defining the limits of the invention.

I claim:

1. In apparatus for producing fire extinguishing foam a hopper for foam forming powder, a water discharge member extending into the hopper through the bottom thereof, a nozzle connected with said member and adapted to discharge a jet of water outwardly through an opening at the bottom of said hopper, and a spray device connected with said member adapted to discharge water into the powder in said hopper and wash the same into the path of said jet.

2. In apparatus for producing fire extinguishing foam a hopper for foam forming powder, a water discharge member extending into the hopper through the bottom thereof, a nozzle connected with said member and adapted to discharge a jet of water outwardly through an opening at the bottom of said hopper, and a device connected with said member adapted to discharge an annular spray of water into the powder in said hopper and wash the same into the path of said jet.

3. In apparatus for producing fire extinguishing foam a hopper for foam forming powder, a water discharge member extending into the hopper through the bottom thereof, said member having a plurality of outlets adapted to discharge water through openings at the bottom of said hopper, and a device connected with said member adapted to discharge a sheet of water into the powder in said hopper and wash the same toward said openings.
